UNITED STATES PATENT OFFICE.

JOHN C. HAASE, OF FARIBAULT, MINNESOTA.

PIANO-BENCH.

1,159,215.

Specification of Letters Patent.

Patented Nov. 2, 1915.

Application filed March 25, 1915. Serial No. 16,925.

To all whom it may concern:

Be it known that I, JOHN C. HAASE, a citizen of the United States, residing at Faribault, in the county of Rice and State 5 of Minnesota, have invented certain new and useful Improvements in Piano-Benches; and I do declare the following to be a full, clear, and exact description of the invention, such as will enable others skilled in the art to 10 which it appertains to make and use the same.

This invention relates to piano benches and more particularly to convertible benches of this character adjustable for use in connection with either a piano of ordinary construction or a player piano, it being desirable with ordinary pianos to have the seat portion of the bench level or horizontal and inclined to the horizontal when used in 20 connection with a player piano.

An object of the invention is to provide a bench of this character which is simple, strong and durable in construction and which may be quickly and easily adjusted to 25 adapt it for use for either of the purposes above specified and which requires no adjusting screws to hold the seat in either position.

Another object of the invention is to provide 30 a seat of this character with the top thereof so connected that it may be raised or lowered to any desired height to adapt it for persons of different heights.

Another object of the invention is to provide 35 a piano bench having a top so mounted that it may be opened from either side and when so opened will remain in upright position and which may also be turned bottom side up and supported on one side member 40 of the bench to adapt it to be used as a table for supporting music when sorting the same.

With these and other objects in view the invention consists of certain novel features of construction and the combination and arrangement of parts as will be more fully described and claimed.

In the accompanying drawings: Figure 1 represents a side elevation of a piano bench constructed in accordance with this invention showing in dotted lines the top slightly elevated and supported in this position; Fig. 2 represents a transverse vertical section taken on the line 2—2 of Fig. 1; Fig. 3 is a longitudinal vertical section showing the top 50 in closed position; Fig. 4 is a transverse vertical section with the top shown in open

position at one side of the bench in full lines and in a similar position at the other side of the bench in dotted lines; Fig. 5 is a detail perspective view of one of the blocks 60 employed for holding the top in inclined position such as it is desirable to have it assume when used in connection with a player piano; Fig. 6 is a width horizontal section. Fig. 7 is a perspective view showing the top 65 in open upright position; and, Fig. 8 is a similar view showing the top open and arranged horizontally to form a support for music when being sorted.

In the embodiment illustrated a seat or 70 bench body is shown in the form of a rectangular box in which music may be kept and which is mounted on the usual legs 1. The side members 2 and 3 of this box 1 are provided adjacent the ends thereof in their 75 upper edges with recesses 4 and 5 respectively the recesses in one side member being disposed in transverse alinement with those in the other side member and which are designed for a purpose to be described. These 80 side members are also preferably provided with locks as 6 for securing the top 6 to be described in closed position when desired. This top or seat board 6 is shown larger than the box 1 so that the ends and side 85 edges thereof overlap the ends and sides of the box as is usual in seats of this character.

Secured to the lower or inner face of the top 6 are brackets 7, a pair of which is arranged near opposite ends of said top, the 90 brackets of each pair being disposed in transverse alinement with each other and those at one end in longitudinal alinement with those of the other end. These brackets 95 as shown are L-shaped and those near one side edge of the top are positioned opposite the recesses 5 in one side member of the box 1 and are designed to extend thereinto when the top is in closed position while the brackets near the other side edge of the top are 100 spaced farther inward to position them beyond the inner face of the adjacent side member of the box 1.

Hinge attaching plates 8 are secured to the opposite side walls of the recesses 4 and 105 are herein shown L-shaped with one arm of each bracket positioned in the recesses 4 and engaged with the side walls thereof, the other arms of said brackets being engaged respectively with the outer faces of the side member of the box containing the recesses 4 and of the supporting legs 2. While these 110

brackets are herein shown and described as L-shaped it is obvious that they may be otherwise constructed and if desired completely housed within the recesses 4.

5 The hinges 9 and 10 which connect the top 6 with the box 1 are similar in construction and hence one only will be described in detail. Each of these hinges comprises four links or bars 11, 12, 13 and 14 which are of 10 equal length and are pivotally connected with each other and with the plates 8 in the following manner. Link 11 is pivoted at one end to the plate 8 which is secured to the inner side wall of the recess 4 and at its 15 other end is pivotally connected with the depending arm of one of the brackets 7 which is secured to the lower face of the top 6 in position to register with the recess 5 in the opposite side member of the box 1. The 20 end of the lever 11 which is pivoted to this bracket 7 is also pivotally connected with one end of the link 12 which extends transversely across the bench top 6 and is rigidly secured to the bracket 7 near the other side 25 of the top and which is arranged in transverse alinement with said first mentioned bracket. The free end of said link 12 projects beyond the bracket to which it is rigidly attached and one end of the link 13 is 30 pivotally connected to this projecting end of link 12. The other end of link 13 is pivotally connected with the inner end of link 14 and the other end of said link 14 is pivotally connected with the attaching plate 8 which 35 is secured to the outer side wall of the recess 4. This end of the link 14 which is connected with the attaching plate 8 is disposed opposite the end of link 11 which is attached to the other plate 8 in the same re- 40 cess 4 and hence a suitable space is provided between these ends of links 11 and 14 and into which the connected ends of links 12 and 13 are adapted to extend when the top 6 is in closed position as will be hereinafter 45 more fully described. The hinge which connects the other end of the top 6 with the box 1 is exactly the same in construction as that above described. The links 11, 12, 13 and 14 of each of the hinges 9 and 10 are of a length slightly less than the width of the box 1 so that when the top is in closed position these links will be completely housed within the box 1 and the recesses 4 and 5 in the upper edges of the side members thereof.

50 For convenience in describing this bench the side member of the box 1 in which the recesses 4 are formed and to which the plates 8 are connected will be termed the front of the bench while that having the recesses 5 55 therein will be termed the rear. When the top 6 has been connected with the box 1 by the hinges 9 and 10 in the manner hereinabove described and the top is in closed position as shown in Fig. 3 and it is desired 60 to open said top from the front of the bench

the lid is raised by grasping the front edge and swinging it upward into the position shown in full lines at the left of Fig. 4 thereby causing the links 12 and 13 to swing on the pivots which connect them with the brackets at the rear edge of the top and with the inner ends of links 14, said pivots serving as pintles for the hinge when so used. When in this position the brackets at the rear edge of the top 6 and the inner ends 75 of links 11 and 14 together with the inner ends of links 11 and 13 are disposed between links 11 and 14 will be disposed within the recesses 5 in the rear wall of the box 1 as is shown clearly in Fig. 4.

When the lid or top 6 is in closed position and it is desired to raise it from the rear side of the bench the rear edge of the top 6 is raised causing the top to assume the position shown in dotted lines at the right of Fig. 4 and when so opened the links from which the hinges 9 and 10 are constructed will be disposed with the links 11 and 12 arranged parallel and extended transversely of the inner face of the top 6 while links 13 and 14 will be in parallel relation and will lie within the recesses 4 and 5 formed in the front and rear walls of the bench, said links 13 and 14 being thus positioned transversely of the box 1. When in this position the pivots which connect the links 11 to the front wall of the box and those which connect links 12 and 13 will serve as the hinge pivots for the cover 6 when in this position, the front edge of the top 6 being disposed below the front wall of the bench 1 and thus holding said top in raised position and preventing it from falling back. When the top is in closed position the links 12 and 13 will be arranged adjacent to each other and will extend between the links 11 and 14 as is shown clearly in Fig. 6.

When it is desired to use the top as a supporting means for music when sorting the same the lid is opened from the front 110 of the bench and the rear edge thereof is raised to disengage it from the rear wall of the bench and said lid is disposed with the outer face of the rear edge thereof resting on the upper face of the end members and the rear wall of the box in which position it is securely held by the links of the hinges which are arranged with links 13 and 14 of each hinge in alinement and 11 and 12 also in alinement, thus positioning links 12 and 13 in parallel relation and links 11 and 14 in parallel relation when the top is so disposed.

Keeper members K and K' are secured to the lower face of the top near the opposite side edges thereof in position to receive the latch of the locks 7 carried by the front and rear walls of the box 1 so that when said top is in closed position it may be securely locked to the box at both the front and rear thereof to 130

prevent all possibility of its becoming loose during shipment and thereby causing injury to the finish thereof.

Each of the end members E of the box 1 is provided in its upper edge with longitudinally spaced aligned sockets 15 which are designed to receive studs 16 on blocks 17 which are designed to be positioned between the upper edges of said end walls and the lower face of the top 6 to lift said top to dispose it in the desired position according to the use for which the bench is to be put or to adapt it for use by taller or shorter persons. As shown these blocks 17 are made wedge shaped or tapered from one end toward the other so that when desired they may be disposed with the inclined or wedge shaped portion arranged between the top and the upper edges of the end members of the box 20 so that said top will be arranged in an incline to adapt the bench for use in connection with player pianos, as it is desirable when pumping or pedaling a piano of this character that the seat be so disposed.

The blocks shown in Fig. 5 for this purpose are inclined on one face only from end to end to adapt them to perform their wedge-like function for supporting the top 6 at an incline and the straight faces of these blocks opposite the inclined face thereof are provided with depending studs 16 for engaging the sockets 15 in the ends of the box 1. When it is desired simply to raise the box top without inclining it these blocks are used with their straight faces 18 and 19 arranged between the lower face of the top 6 and the upper edge of the ends E of the box 1 and when so disposed studs 16' which depend from the face 19 are designed to enter the sockets 15 of the end members of the box and thus securely hold said blocks in operative position.

One block only is shown for use in connection with this top but it is to be understood that any desired number may be employed the different blocks being of different heights to provide for the raising of the top the desired height according to the blocks which are placed thereunder and it is to be understood that all of the blocks are provided with studs for holding them in engagement with the sockets 15 of the end members of the box.

From the above description it will be obvious that the top of this bench may be opened either from the front or from the rear and when so opened will be automatically held in raised position without danger of its falling either forward or backward, to provide access to the interior of the box and to permit the user to employ both hands in sorting music contained therein. This top may also be adjusted at any desired height by positioning blocks of the desired height between such top and the box without in

any way interfering with the operation of the hinges thereof which by their peculiar construction provide for the adjustment of the top.

I claim as my invention:

1. In a piano bench the combination of a body, a cover therefor adapted to form a seat, cover supporting means interposed between the body and the cover and comprising a plurality of pivotally connected links, one of said links extending transversely of said cover and fixedly mounted thereon, a link pivoted at one end to one end of said fixed link and at its other end to one side of said body, another link pivoted at one end to said body side, and a link pivoted to the free end of said last mentioned link and to the free end of said fixed link. 70

2. In a piano bench the combination of a body, a cover therefor adapted to form a seat, cover supporting means interposed between the body and the cover and comprising a plurality of pivotally connected links, one of said links extending transversely of said cover and fixedly mounted thereon, a link pivoted at one end to one end of said fixed link and at its other end to one side of said body, another link pivoted at one end to said body side, and spaced longitudinally from the other link pivoted thereto, 95 and a link pivoted to the free end of said last mentioned link and to the free end of said fixed link. 90

3. In a piano bench the combination of a body, a cover therefor adapted to form a seat, cover supporting means interposed between the body and the cover and comprising a plurality of pivotally connected links, one of said links extending transversely of said cover and fixedly mounted thereon, a link pivoted at one end to one end of said fixed link and at its other end to one side of said body, another link pivoted at one end to said body side, and a link pivoted to the free end of said last mentioned link and to the free end of said fixed link, all of said links being of the same length, said fixed link and one of the links pivoted thereto being foldable between the other two links when the cover is closed. 105 110 115

4. In a piano bench the combination of a box having oppositely disposed recesses in the side members thereof, a link fixed to the lower face of said cover in vertical alignment with said recesses, two links pivotally connected at one end to the opposed walls of one of the recesses in said box, the free end of one of said links being pivoted to one end of said fixed link, an intermediate link pivoted at one end to the free end of the other of said box connected links, the other end of said intermediate link being pivoted to the free end of said fixed link. 120 125

5. In a piano bench the combination of a box having an oppositely disposed recess in

the side members thereof, hinge attaching plates secured to the opposite side walls of one of said recesses, brackets secured to the lower face of said cover in vertical alinement with said recesses and in transverse alinement with each other, a link extending transversely of said cover and fixed to said brackets, two links pivotally connected at one end of the opposed attaching plates of said recesses, the free end of one of said links being pivoted to one end of said fixed link, an intermediate link pivoted at one end to the free end of the other of said box connected links, the other end of said intermediate link being pivoted to the free end of said fixed link.

6. A piano bench comprising a box, a cover therefor adapted to form a seat, a link

pivoted at one end to one side of said box and at its other end to the cover at the opposite side of the box and on the lower face thereof, and another pair of pivotally connected links, the free end of one pivoted to the same side of the box to which the first mentioned link is pivoted and the free end of the other pivoted to the cover at the side opposite that to which the first mentioned link is connected.

In testimony whereof I have hereunto set my hand in presence of two subscribing witnesses.
